UNITED STATES PATENT OFFICE.

MONTGOMERY H. WATSON, OF DAYTON, OHIO.

TALLYING-SHEET.

No. 867,325.

Specification of Letters Patent.

Patented Oct. 1, 1907.

Application filed March 20, 1907. Serial No. 363,437.

To all whom it may concern:

Be it known that I, MONTGOMERY H. WATSON, a citizen of the United States, residing at Dayton, in the county of Montgomery and State of Ohio, have invented 5 certain new and useful Improvements in Tallying-Sheets; and I do declare the following to be a full, clear, and exact description of the invention, such as will enable others skilled in the art to which it appertains to make and use the same, reference being had to the accompanying drawings, and to the letters and figures of reference marked thereon, which form a part of this 10 specification.

My invention relates to new and useful improvements in tally sheets for tallying votes, and has for its object 15 the provision of a tally sheet which greatly facilitates the work of election clerks or judges, owing to the work being brought within a comparatively narrow compass. In other words, instead of employing the usual lengthened tally sheet which necessitates the eye of the clerk 20 following for a considerable distance, the particular line opposite the candidate's name whose vote is being tallied, the tally sheet of the present invention is constructed to obviate this objectionable feature by bringing the work within a comparatively narrow compass 25 thus obviating the necessity of the clerk following with the eye and hand the proper line to a remote point from the name of the candidate whose vote is being tallied. These desirable objects are accomplished by 30 means of the tally sheet illustrated in the accompanying drawing, to which particular reference is now made.

The sheet A on the left is divided into a plurality of spaces B, the number of such spaces corresponding to the number of tickets, and each of which spaces is of proper dimensions to suit the number of candidates running 35 on each particular ticket. The names of the tickets and the names of the respective candidates on each ticket appear on the extreme left hand side of said sheet A. Each of the spaces or divisions thus devoted to each ticket is provided at its head with numerals indicating the number of votes as tallied in 40 each square of the vertical columns, said figures ranging from five upward in multiples of five up to the limit which in the drawing is shown to be fifty. Bound to the leaf A along the line C, is a supplemental tally sheet D of a width to extend to the right hand end of the spaces taken up with the candidates' names on the sheet A, when said supplemental sheet D is laid over upon said sheet A as shown at the "Socialist" ticket 45 space or division on said sheet A. This supplemental sheet D is of a width equal to the width of the portion of sheet A upon which the votes are tallied opposite the names, and the said supplemental sheet is provided with a series of transverse perforated lines E which are in line with the lower terminals of the ticket divisions or 50 spaces on sheet A, so that the said supplemental sheet D comprises a series of fly leaves F corresponding to the divisions or spaces on sheet A. The said supplemental sheet D when its spaces are filled with the tally marks on one side, and which are continuations of the tally marks on sheet A, may be turned over as shown at the Socialist ticket division, and the other side of said supplemental sheet D may be utilized by continuing the tally marks thereon. In so turning over said supplemental sheet D or a section F thereof to be utilized in connection with any particular ticket, the section 60 of said supplemental sheet to be so utilized is detached from the remainder of the sheet along the perforated line E as shown in the Socialist ticket section. The supplemental sheet D so constructed of the sections or divisions F, is joined to an under sheet H which is a 65 continuation thereof and which is likewise divided into sections or divisions G, each of which is utilized in connection with a respective ticket when the two sides of all the sections F or of any one section F of the supplemental sheet of leaf D is filled. For example, the "So- 70 cialist" ticket contains on the initial section B spaces for tallying fifty votes; this is true of the other spaces or sections of the sheet A; after these tally spaces have been filled, that particular section F of the supplemental tally sheet D is filled on its initial side to tally 75 one hundred votes, the section of the supplemental sheet D so filled on one side is then turned over and the other side is utilized to continue the tally of the votes of that ticket up to its capacity which is one hundred and fifty votes. If the votes of the "Socialist" ticket 80 or any other ticket, for example, exceeds that number, the particular section G of the under leaf or sheet H is utilized to continue the tally as shown in connection with the tally of the Socialist vote.

It will be seen from the above description taken in 90 connection with the drawing, that if the votes of any one particular ticket exceed in number those of another ticket, the particular section or division F of the supplemental sheet D and the corresponding section or division G of the under sheet H may be utilized for tallying the vote of that particular ticket by detaching the section F of the supplemental sheet along the perforated line E. The work of tallying the votes is thus brought within a comparatively small space; this renders the work of the clerk much less tedious and troublesome and more accurate than is possible by the use of a single tally sheet with the candidates' names at one extreme side of the sheet and the tally spaces reaching a remote distance from said names to the other side of the sheet; or by the use of a single sheet of smaller 95 dimensions where a single sheet is used for tallying the votes of a single ticket, thus requiring a constant turning of sheets in order to tally the votes of each ticket. By the use of the tally sheet herein shown and described, the ticket headings and the names of the candidates 100 of each ticket are arranged upon a single sheet divided into distinct spaces and are always within the ordinary 110 range of the vision. By means of the sectional supplemental sheet D which forms a continuation on both sides of the sheet upon which the candidates' names appear, and the under sheet H which is united to said sheet D and forms a continuation of said supplemental sheet D, the work of tallying the votes of each ticket is, as before stated, brought within a comparatively small space and the work is greatly facilitated.

The fly leaves or sections F of the supplemental tally sheet D are provided on the opposite sides with appropriate figures arranged in the progressive order and which indicate the votes as tallied in each of the tally spaces, and likewise the sections G of the under sheet H is provided with figures to indicate the number of votes tallied thereon.

I claim:

A tally sheet comprising an initial sheet divided into sections each section containing the name of a ticket and the names of candidates and a series of spaces on one side of said names formed by lines extending at right angles, 20 a supplemental sheet of a length equal to that of said initial sheet and of a width equal to the portions of the initial sheet which contain said spaces, said supplemental sheet having a series of spaces on both sides formed by lines extending at right angles and corresponding in 25 number and alining with the spaces on the initial sheet, said supplemental sheet being provided with a series of transverse lines of perforations dividing it into sections equal in number and area to the portions of the sections of the initial sheet which contain the spaces, and a final sheet of a length equal to the length of the initial sheet or the supplemental sheet, said final sheet being provided with a series of spaces formed by lines extending at right angles and equal in number and area to the spaces on the initial sheet or one side of the supplemental sheet. 30 35

In testimony whereof I affix my signature, in presence of two witnesses.
